UNITED STATES PATENT OFFICE.

GUSTAVE M. FAUSER, OF NEW YORK, N. Y.

DESIGN FOR A WOVEN RUG.

42,320.

Specification for Design.

Patented Mar. 19, 1912.

Application filed June 1, 1911. Serial No. 630,690. Term of patent 3½ years.

To all whom it may concern:

Be it known that I, GUSTAVE M. FAUSER, a citizen of the United States of America, residing in the borough of Manhattan, in the city of New York, in the county and State of New York, have invented a new, original, and ornamental Design for a Woven Rug, of which the following is a specification, reference being had to the accompanying drawing, forming part thereof.

The figure of the drawing is a view of a rug showing my new design.

The design consists of a collection of outer border stripes, the central one A, being broader than the others and characterized

by a series of rosettes b, b. The central portion or body is filled with an arrangement of oblong figures, B, B.

A principal feature of the design resides in the irregular lines a, a, which run through the body of the rug and give it a moire-antique or watered effect beneath the main figures.

I claim:

The ornamental design for a woven rug as shown and described.

GUSTAVE M. FAUSER.

Witnesses:

AUGUSTA SCHWARZ,
OSCAR W. FAUSER.
